UNITED STATES PATENT OFFICE

MARCEL M. MICHELIN, OF STATEN ISLAND, NEW YORK, ASSIGNOR TO PINAUD INCORPORATED, OF NEW YORK, N. Y., A CORPORATION OF NEW YORK

POWDER CONTAINER

Application filed November 8, 1929. Serial No. 405,775.

This invention relates to a box which is particularly adapted for use as a powder container.

It is an object of the invention to produce a box which is substantially and attractively built and which will retain the powder content without the possibility of the latter dusting from the box.

It is a further object of the invention to produce a triangular box of this nature.

It is still a further object of the invention to provide a triangular box, the body and cover of which are composed of paper or cardboard and the bottom of which consists of bakelite or a similar material, and which is so attached to the body of the box that it will seal the latter and will be retained in its attached condition.

In the drawings:

Fig. 1 is a perspective view of the box with the cover in place;

Fig. 2 is an exploded perspective view of the box;

Fig. 3 is a sectional view on line 3—3 of Fig. 1;

Fig. 4 is a plan view of the blank used to form the body of the box;

Fig. 5 is a perspective view of the body of the box after it has been assembled;

Fig. 6 is a plan view of the blank used in the making of the cover of the box;

Fig. 7 is a perspective view of the cover partly broken away to illustrate the construction;

Fig. 8 is a plan view of the bottom of the box; and

Fig. 9 is an enlarged fragmentary view.

The box consists of a base 1, a self-contained body portion 2 and a cover 3. In the embodiment illustrated in the drawings, the base, body portion and cover are triangular in form, and while certain phases of the invention relate particularly to this form in a broader aspect the invention contemplates the construction of the box in various forms.

The body of the box includes a side wall 4, a bottom 5 and a top 6. The side wall is made of one continuous strip of material, preferably cardboard. This continuous strip of cardboard is bent into triangular

form and the end edges are brought together so that it is in this condition open at the top and bottom. This side wall is maintained in its triangular form by the top 6, which is preferably of paper. This top is folded over the upper edge of the side wall 4 and secured to the outer faces of the side wall by suitable adhesive. A strip 7, preferably of paper, covers the side wall and is secured thereto by an adhesive, so that its upper edge overlies the turned over edges of the top 6 (see Fig. 5).

Thus, the side walls of the body portion are maintained in their triangular form and the cover closes the body portion at the top.

The bottom 5 of the body portion is triangular in form and of a size adapted to close the bottom of the body portion of the box.

This bottom 5 is secured to the lower edge of the side wall 4 by a strip 8, which is secured to the bottom by adhesive and to the outer faces of the side wall by adhesive beneath the strip 7.

The bottom of the body portion on the box is made up of laminated material suitably secured together and in the lower

lamination is an opening 9. In the upper lamination is an opening 10 of a less diameter than the opening 9. The abutment 11 is formed by these different sized openings.

These openings in the bottom portion of the box are closed by a removable seal 12, which is formed as a result of the cutting of the opening 9.

When this seal is in place it will snugly fit the opening 9 and be retained therein by friction and yet easily removable, and it will be prevented from entering the interior of the body portion of the box by the abutment or flange 11.

Thus the body portion of the box will be a complete powder container unit which can be filled by the removing of the seal 11 after the various parts of the body portion have been assembled, as described.

This body portion of the box thus assembled is attached to the base 1. This base 1 is made preferably of bakelite or a similar material, and is provided with a depression or seat 13 for the reception of the body portion of the box. This depression is formed by a flange 14 which surrounds the edge of

the bottom. At the inner side of the flange are walls 15 which form a triangle substantially the same size as that formed by the outside of the wall of the body of the box and are sufficiently deep to embrace a considerable portion of the side walls of the body of the box. The relation between the size of these two triangles is such that the body of the box may be forced into the depression 13 and will snugly fit therein, so that there will be a frictional engagement between the walls 15 and the flange of the walls of the side of the body of the box to assist in maintaining the body of the box and the bottom in assembled relationship. This assembled relationship is further insured by the securing of the bottom of the body of the box to the bottom of the depression 13 of the bottom by adhesive which covers the contacting surface of the bottom of the body of the box.

The side walls of the cover of the box are made from a single strip 16 of material which is scored along lines 17 from the outside toward the inside of the strip, but only partly through the strip so that the inner surface of the strip is unbroken and unscored. This strip is bent into triangular form so that the end edges abut each other and is formed preferably of relatively stiff cardboard. These side walls of the cover are held in their triangular form by a strip 18 which covers the outer face of the walls of the cover, is relatively thinner than the material from which the side walls are formed and is secured thereto by an adhesive. The top of the cover is of a triangular form and is composed of a laminated material, the inner lamination 19 being equal to the inside measurements of the triangular wall of the cover and in assembled condition abutting against the inside of the walls as at 20. The outer lamination 21 is greater in size than the inner lamination 19 to an extent equal to the thickness of the materials making up the walls of the cover. The result of this formation of the top of the cover from laminations of different sizes is that a flange 22 is provided on which the lower edges of the walls of the cover rest. The top of the cover of the box is secured to the side walls by a relatively lighter and more flexible material, such as paper 23. This is secured to the outer face of the top by an adhesive and overlaps the outer face of the side walls and the top. The side walls and these overlapping edges are covered by a paper cover 24 which is folded over the free edges of the side walls and secured to the outer faces of the side walls, as well as to the inner faces to the extent to which the paper overlaps them.

The flange 14 of the bottom of the box forms an abutment or ledge 25 which is of a width equal to the width of the material of the side walls of the cover. The width of the side walls 7 and the body of the box is

less than the width of the side walls 16 of the cover of the box, so that when the cover envelopes the body of the box the lower edge of the side walls of the cover will rest upon the abutment or ledge 25 of the bottom.

The size of the triangle formed by the body of the box is substantially equal to the size of the triangle formed by the inside wall of the cover of the box, so that the cover is held upon the body of the box by frictional engagement.

What I claim is:

1. In a box of the class described, a triangular self-contained body portion, a triangular cover therefor, a triangular bottom of unyielding material for the box having a depression therein for receiving the body portion, the side walls of said depression frictionally engaging the outer faces of the side walls of the body portion of the box.

2. In a box of the class described, a triangular self-contained body portion formed of a single strip of material, a triangular cover therefor, a triangular bottom for the box of relatively greater thickness than that of the body of the box having a depression therein for receiving the body portion, the side walls of said depression frictionally engaging the outer faces of the side walls of the body portion of the box, and an adhesive for securing the adjacent faces of the bottom and the body portion of the box together.

3. In a box of the class described, the combination with a body portion, a bottom and a cover, said cover having side walls formed of a single strip of material, means for securing said material in a predetermined form, said cover having a top, the top being formed of laminations of different sizes, the edges of the inner diameter adapted to abut against the inner face of the side walls of the cover and the upper edges of the side walls of the cover adapted to abut against the outer lamination, and means common to said laminations for securing the latter to the side walls of said cover.

In testimony whereof, I have signed my name to this specification this 5th day of November, 1929.

MARCEL M. MICHELIN.
